UNITED STATES PATENT OFFICE.

ALBERT E. GRUBB AND THOMAS J. BURY, OF ENID, OKLAHOMA.

SANITARY GARBAGE-CAN.

1,039,050.

Specification of Letters Patent. Patented Sept. 17, 1912.

Application filed July 18, 1911. Serial No. 639,089.

To all whom it may concern:

Be it known that we, ALBERT E. GRUBB and THOMAS J. BURY, citizens of the United States, residing at Enid, in the county of 5 Garfield and State of Oklahoma, have invented new and useful Improvements in Sanitary Garbage-Cans, of which the following is a specification.

The general objects of the invention are to 10 facilitate the operation of raising the closures of garbage cans; to adapt these closures to descend automatically following the depositing of garbage in the can; and to simplify the operation of removing the garbage from the can.

Other objects will appear and be better understood from the following description taken in connection with the accompanying drawings, in which,

20 Figure 1 is a vertical longitudinal section of the device. Fig. 2 is a view similar to Fig. 1 but taken on a plane at right angles to the plane of Fig. 1. Fig. 3 is a detail perspective of the upper end portion of the can 25 showing the cover raised.

The body 5 or outer receptacle is herein shown as formed of sheet metal, although, the body or outer receptacle may be formed of other material found suitable for the purpose. The body or outer receptacle 5 is preferably though not necessarily cylindrical in 30 contour and is open at either end and the supporting legs 6 connected to the lower end of the body or outer receptacle serve to support the same in spaced relation to the ground.

The lid or cover 7 is preferably formed of the same material as the body or outer receptacle 5 and is herein shown as connected to 40 the latter by a hinge 8 and has a resilient latch 9 which springs over the beaded upper edge 10 of the body or outer receptacle 5. It will be understood, however, that this connection is merely illustrative of one embodiment of the invention and the hinge connection may be dispensed with if desired, in which event the cover, when arranged on the receptacle, will be secured against displacement in any well-known manner.

50 The gravity closures 11 normally seal the ports or openings 12 in the lid or cover 7. These elements are made so as to be raised with a minimum of effort on the part of the operator and I have found that this result is 55 attained by forming the closures substantially sector-shape in contour and suitably

connecting them to the lid or cover such as by hinges 13. In the present instance, the parts conform to the configuration of the closures and are slightly less in area than 60 the latter so as to be completely sealed when the closures are lowered as shown. It is to be understood that we are not to be limited to the specific configurations of the closures and ports, since, the result above stated may 65 be attained by forming the closures into other shapes. The mechanism for raising the closures is herein shown to consist of a connecting rod 14 arranged in a guide 15 on the inner face of the outer receptacle or 70 body 5 and having at one end a pedal 16 extending laterally beyond the lower end of the body or outer receptacle 5. A lever 17 is pivotally connected in any preferred manner to the lid or cover 7 such as by a hook 75 18, which is received by an eye 19 depending from the lid or cover 7. The lever connects at one end with the upper end portion of the connecting rod 14 and a pin and slot connection 20 is made between the opposite 80 end of the lever and one end portion of an arm 21 which is pivotally connected, as shown at 22, to the lid or cover 7. The free end portion of the arm carries a yoke 23, the levers 24 of which underlie the closures 11. 85 With this construction it will be seen that the levers 24 of the yoke will move upwardly and lift the closures when the pedal 16 is depressed. When the force which depresses the pedal is removed therefrom, the parts 90 will gravitate to their normal positions as shown in Figs. 1 and 2.

The stop 25 connected to the central portion of the lid or cover 7 is arranged so that its opposite ends will form abutments for 95 the closures when the latter are raised, whereby, to prevent the closures from moving beyond the vertical when the pedal is depressed, thus, insuring the descent of the closures when the pedal is released as previously described.

The inner receptacle 26 for the garbage is herein shown as formed of textile material and conforms to the shape of the ordinary bag and has openings adjacent to its 105 mouth to receive hooks 27 arranged at spaced intervals around the upper end portion of the outer receptacle or body, whereby, the said inner receptacle may, when filled with garbage, be readily removed from 110 the outer receptacle or body, placed in a collecting wagon and an empty inner re-

ceptacle placed in its stead in the outer receptacle or body and connected as shown.

The device is chiefly intended as a depository for dry garbage, such as paper, fruit skins and the like and to be placed on street corners or other available portions of streets, such as in front of stores wherein it may be used as an advertising medium, since, the name of the owner or advertiser

10 may be printed thereon.

By providing one or more than one port in the lid or cover 7, enables the operator, when holding the garbage in either his right or left hand, to deposit the garbage in the 15 can with the hand holding the same. By spacing the lower end of the outer receptacle from the ground insures a free circulation of air around the inner receptacle and the contents thereof and also prevents the collection or the retaining of garbage or other 20 foreign matter by the outer receptacle and the consequent foul odors.

Although we have shown and described one embodiment of our invention it is to be 25 understood that we are not to be limited to the specific structure nor to the particular arrangement of the parts, herein shown and described since it will be seen that various changes will be made, in the scope of the 30 appended claims without departing from the spirit or sacrificing any of the advantages of the invention.

What we claim as new is:

1. A garbage can comprising a body, a 35 removable receptacle suspended within the body, a ported cover closing the receptacle, gravity closures for the ports of the said cover, a lever arranged within the body and pivotally supported by the said cover, an 40 arm pivoted to the cover and connected to one end of the said lever, means supported by the said arm and adapted to engage the said gravity closures to move the same to an open position and a foot actuating rod connected to the opposite end of the said lever 45 substantially as and for the purpose described.

2. In a garbage can comprising a body, a ported cover connected thereto, gravity closures for the ports of the said cover, an arm 50 pivotally supported by the under side of the cover, a lever carried by the cover and having its free end connected to the said arm by a slot and pin connection, means carried by the said arm and adapted to engage said gravity closures to move the same to an open position and a foot actuating rod connected to the opposite end of the said lever substantially as and for the purpose described. 55

3. In a garbage can comprising a body being open throughout, a ported cover connected thereto, gravity closures for the ports of the said cover, a lever pivotally supported by the cover intermediate its ends, a 60 movable arm carried by the cover and disposed above the said lever and connected to one end thereof, an actuating member supported by the said arm and adapted to engage the said gravity closures to move the 65 same to an open position and a foot actuating rod connected to the opposite end of the lever substantially as and for the purpose described. 70

4. In a garbage can comprising a body, a 75 ported cover connected thereto, gravity closures for the ports of the said cover, an arm pivoted to the under side of the said cover, a lever pivotally supported by the cover and having its free end connected to 80 the said arm, a foot actuating rod connected to the opposite end of the said lever, and a U-shaped actuating member supported by the said arm and adapted to contact the said gravity closures to move them to an open 85 position.

In testimony whereof we affix our signatures in presence of two witnesses.

ALBERT E. GRUBB.
THOMAS J. BURY.
